P. H. YAWMAN.

LOCK,

APPLICATION FILED MAY 24, 1916.

1,261,089.

Patented Apr. 2, 1918.

UNITED STATES PATENT OFFICE.

PHILIP H. YAWMAN, OF ROCHESTER, NEW YORK, ASSIGNOR TO YAWMAN & ERBE MFG. CO., OF ROCHESTER, NEW YORK, A CORPORATION OF NEW YORK.

LOCK.

1,261,089.

Specification of Letters Patent. Patented Apr. 2, 1918.

Application filed May 24, 1916. Serial No. 99,686.

To all whom it may concern:

Be it known that I, PHILIP H. YAWMAN, of Rochester, in the county of Monroe and State of New York, have invented certain new and useful Improvements in Locks; and I do hereby declare the following to be a full, clear, and exact description of the same, reference being had to the accompanying drawings, forming a part of this specification, and to the reference-numerals marked thereon.

My present invention relates to locks and it has for its object to provide a key lock especially adapted for the particular requirements of filing containers whereby in a tumbler lock of the cylinder type the key may be withdrawn with the parts in the unlocked position and the same later moved to locked position without the use of the key. The improvements are also directed toward simplicity of design and manufacture and to these and other ends the invention resides in certain improvements and combinations of parts all as will be hereinafter more fully described, the novel features being pointed out in the claims at the end of the specification.

In the drawings:

Figure 1 is a vertical sectional view through a filing cabinet provided with a lock constructed in accordance with and illustrating one embodiment of my invention;

Fig. 2 is an enlarged sectional view taken axially through the lock with the plug and casing in locking register but showing the key inserted to displace the locking pin;

Fig. 3 is a transverse section taken substantially on the line 3—3 of Fig. 2;

Fig. 4 is a view similar to Fig. 2 but showing the plug rotated to a position in which the key may be withdrawn, and

Fig. 5 is a transverse section taken substantially on the line 5—5 of Fig. 4.

Similar reference numerals throughout the several figures indicate the same parts.

In Fig. 1 is shown a familiar type of filing cabinet embodying a casing 1 containing a drawer chamber 2 in which operates a drawer 3. The drawer is secured in closed position by a pivoted latch 4 entering an

aperture 5 in the rear wall of the drawer. The latch 4 is carried on a vertically movable lock bar 6 which, upon being raised, releases the latch and when in lowered position holds the latter ready to snap into engagement with the drawer under the influence of a spring 7.

The raising and lowering of the rod 6 is accomplished through the rotation of a rod 8 journaled in a bracket 9 secured to the bottom wall of the chamber 2 and depending therefrom. The rear end of the rod 8 has an eccentric portion 10 journaled in the vertical lock bar 6 and a half rotation of the rod 65 in one direction raises the bar while a half rotation in the other direction lowers it.

A key lock that controls the rotation of the rod 8 is mounted upon a front arm 11 of the bracket 9 and thus the latter and the rod and lock constitute a single locking unit that can readily be applied in assembled condition to the cabinet. The lock consists preferably of a cylindrical casing 12 and a rotatable plug 13 running longitudinally therethrough and joined at its rear end, concentrically, to a coupling sleeve 14 in which the forward end of the rod 8 is secured. The plug may also extend through the bracket arm 11 to which the case 12 is attached 80 and adjacent to this arm 11 the sleeve 14 is provided with a laterally projecting pin 15 that engages stop pins 16 and 17 on the arm to define the unlocked and locked positions of the plug and of the latch 4 and to 85 limit the rotation of the plug and rod 8 to a half revolution.

The case 12 and plug 13 are provided with pin chambers 18 and 19 in which operate drivers 20 and pins 21, the drivers being 90 pressed by springs 22. The chambers 19 and pins 21 intersect a flat keyway 23 extending longitudinally of the plug 13. When the key 24 is inserted, the bits 25 thereof raise the pins 21 each to a sufficient height so that 95 the end faces of the pins and the end faces of the drivers 20 will be coincident with the periphery of the plug 13, permitting rotation of the latter and the release of the lock. Ordinarily, however, when the chambers 18 and 19 are in register in locking position, the drivers are thrust down past the

periphery of the plug and interlock the latter with the case, the pins 21 retreating different distances within the keyway 23.

Ordinarily with a lock of this kind, the 5 rotation of the plug from locking position prevents removal of the key for the reason that the bits 25 thereof interlock with the pins 21 and the latter cannot yield because they are held against the walls of the bore 10 in which the plug rotates against any axial movement until they are again in alignment with the chambers 18 and the yielding drivers 20. This is desirable in most instances perhaps as it prevents the operator 15 from withdrawing the key in the belief that the device is locked when, as a matter of fact, it is unlocked but in the case of filing devices, it is usual to lock the drawers or similar elements up at night but, after unlocking them in the morning, to leave them 20 unlocked for the day or while they are to be in constant use.

I therefore provide in a wall of the case 12 a yielding portion 26 into which the pins 21 may be brought to register after leaving 25 their locking position of register with the chambers 18 and drivers 20 which latter position is shown in Fig. 3. In the present instance, this yielding wall consists of a 30 block normally pressed against the periphery of the plug 13 by a spring ring 27 encircling the case 12. When the plug is rotated a half revolution to the unlocked positions of Figs. 4 and 5 and it is sought to 35 remove the key 24 the pins 21 are permitted to ride over the bits of the key as they can press outwardly the block 26 which latter, through its spring 27, returns the pins flush with the periphery of the plug after the 40 key is out. It is then unnecessary to reinsert the key in order to lock the plug again (though it may be done in this way) for I provide an extension 28 on the plug 13 constituting a forwardly projecting knob that 45 can be twirled with the fingers to bring the plug back to locked position. Once this locked position is reached, however, it is, of course, impossible to use the knob to rotate the plug again until the key has been inserted and the pins properly displaced.

The yielding wall or member 26 is, in the present embodiment, arranged diametrically opposite the driver chambers 18 providing for a half rotation of the plug to 55 reach an unlocked and key-withdrawing position but this is because the particular latch mechanism for the drawer first described requires this movement. It will be readily seen, however, that a lesser or greater degree of rotation could as easily be provided for as the yielding portion 26 could be placed at any point on the peripheral path of the plug.

With a filing device locked in the manner

above described, an employer may, with one 65 use of his key, unlock the filing device for continuous use during a period at the end of which a clerk or other person may be relied upon to relock it through the use of the knob 28, after which it can not be again 70 unlocked without the employer's key.

I claim as my invention:

1. In a lock, the combination with a case, a key receiving plug rotatable therein, there being registerable pin chambers in both case 75 and plug, and pins operating in the chambers, of a key adapted to enter the plug and to displace the pins, the case being formed to allow displacement of the pins and withdrawal of the key after a partial rotation 80 of the plug, means for returning the pins to the position in which they were held by the key, and means independent of the key for rotating the plug back to locking position.

2. In a lock, the combination with a case, 85 a key receiving plug rotatable therein, there being registerable pin chambers in both case and plug, and pins operating in the chambers, of a key adapted to enter the plug and to displace the pins, the case being formed 90 to allow displacement of the pins and withdrawal of the key after a partial rotation of the plug, means for returning the pins to the position in which they were held by the key, and an extension on the plug independent 95 of the key and forming a knob by means of which the plug may be rotated back to locking position.

3. In a lock, the combination with a case, 100 a key receiving plug rotatable therein, there being registerable pin chambers in both case and plug, and pins operating in the chambers, of a key adapted to enter the plug and displace the pins, and a yielding wall in the casing permitting the pins to ride the bits 105 of the key upon withdrawing movement of the latter while the plug is out of locking position, said wall tending to hold the pins within the chambers in the plug while in engagement therewith.

4. In a lock, the combination with a case, 115 a key receiving plug rotatable therein, there being registerable pin chambers in both case and plug, and pins operating in the chambers, of a key adapted to enter the plug and 120 displace the pins, and a yielding wall in the casing permitting the pins to ride the bits of the key upon withdrawing movement of the latter while the plug is out of locking position, said wall tending to hold the pins within the chambers of the plug while in engagement therewith, and means independent of the key for rotating the plug back to locking position.

5. In a lock, the combination with a cylinder case, a key receiving plug rotatable therein, there being registerable pin chambers in both case and plug, and pins oper-

ating in the chambers, of a key adapted to enter the plug and displace the pins, a displaceable wall in the cylinder case permitting the pins to ride the bits of the key upon withdrawing movement of the latter while the plug is out of locking position, and a spring ring encircling the cylinder case to press upon the displaceable wall and hold

the pins within the chambers in the plug while the said wall is in engagement therewith.

PHILIP H. YAWMAN.
